UNITED STATES PATENT OFFICE.

JAMES H. SPARGER, OF MOUNT AIRY, NORTH CAROLINA.

DESIGN FOR A BLOCK OR BODY OF PLUG-TOBACCO.

SPECIFICATION forming part of Design No. 25,959, dated August 18, 1896.

Application filed March 20, 1895. Serial No. 542,545. Term of patent 7 years.

To all whom it may concern:

Be it known that I, JAMES H. SPARGER, a citizen of the United States, residing at Mount Airy, in the county of Surry and State of North Carolina, have invented and produced a new and original Design for a Block or Body of Plug-Tobacco; and I do hereby declare the following to be a full, clear, and exact description of the same, reference being had to the accompanying drawing, forming a part thereof.

The leading feature of my design consists in a body or block of plug-tobacco having a square face divided by parallel lines into rectangles, each rectangle comprising an even number of squares and each square having thereon an inscription arranged diagonally, the inscriptions being arranged so that they can always be read from left to right, no matter in what position the block is held.

In the accompanying drawing, illustrating my design, the numeral 1 designates a four-sided inclosure, and 2 designates the face of the block or body of tobacco within the same, while 3 designates the parallel lines dividing the face of the block into a series of rectan-

gles 4, and 5 designates the inscriptions arranged as previously described.

A series of lines 6 may extend transversely across the rectangles, thus indicating the squares comprised within the rectangles.

The arrangement described will cause the inscriptions on one rectangle to lie directly over the inscriptions of another rectangle if the block be formed of a series of layers laid one upon the other, the rectangles of one layer extending transversely across those of the other layer, and as a consequence the appearance of the face of the block looking down on the same will be preserved even though portions of one layer be removed from over the layer next below.

Having thus described my invention, what I claim is—

The design for a block of plug-tobacco, shown and described.

In testimony whereof I affix my signature in presence of two witnesses.

JAMES H. SPARGER.
